COMBINED MAGNET, DISPENSER AND SPONGE
FOR CLEANING WINDOWS OR THE LIKE

Orlando A. Gaudino, R.D. 4, Butler, Pa.

Filed Sept. 9, 1964, Ser. No. 31,660

Term of patent 14 years

(Cl. D9—2)

FIGURE 1 is a side elevational view of a combined magnet, dispenser and sponge for cleaning windows, or the like, showing my new design.

The side not shown is substantially like the side shown. The opposite end to that shown has an opening, which extends from top to bottom and conforms throughout to the shape as indicated in FIGURE 2.

I claim:

The ornamental design for a combined magnet, dispenser and sponge for cleaning windows or the like, as shown and described.
